UNITED STATES PATENT OFFICE.

HENRY J. ROBINSON, OF WASHINGTON, DISTRICT OF COLUMBIA, ASSIGNOR TO RIEMAN & DAWSON, OF SAME PLACE.

DESIGN FOR A SPOON, &c.

SPECIFICATION forming part of Design No. 23,747, dated October 30, 1894.

Application filed September 28, 1894. Serial No. 524,404. Term of patent 7 years.

To all whom it may concern:

Be it known that I, HENRY J. ROBINSON, of the city of Washington, in the District of Columbia, have invented a new and original 5 Design for Handles of Spoons, &c., of which the following is a specification.

10 The leading features of my design comprise the representation of the "Uncle Sam" Brownie applied to and forming the extreme end of the handle and having the appearance of having climbed to and seated himself 15 astride of the upper end of the handle, one arm being held akimbo, the whole figure forming the upper marginal edge of the handle. Below "Uncle Sam" is seen the "Irishman" his left arm reaching for the right leg of 20 "Uncle Sam," while his right limbs embrace the edge of the handle in his endeavors to climb to the top. Below and to the left of the "Irishman" appears the "Dude" clinging to the leg of the "Irishman" with one 25 hand, while in the other is tightly clasped the cane, his monocle and beaver being undisturbedly held in place. Directly below the "Dude" is the "Chinaman" his arms and legs clasping the edge of the handle, appearing as if vainly attempting to reach the position 30 occupied by the "Dude." A short distance below, the "Policeman" appears, with club in hand, and clinging to the roughened surface of the handle, and having the appearance of having stopped to look upward to see 35 how much farther he had to go before catching a little Brownie directly above and out of his reach. Beneath the "Policeman" on the lower end of the handle appear several other Brownies all endeavoring to reach the pinnacle occupied by "Uncle Sam."

40 The several parts of the different figures form the marginal edges of the handle. Upon the reverse side of the handle are formed representations of the "Indian" Brownie, and 45 several other Brownies, having marked characteristics of their tribe.

50 The whole design forms a neat and amusing design for the handles of spoons, forks and similar articles.

Having thus described my invention, what I claim is—55 1. The design for the handles of spoons, forks and similar articles substantially as herein shown and described.

2. In a design for the handles of spoons and similar articles, the obverse, substantially as shown and described.

60 3. In a design for the handles of spoons, forks and similar articles the reverse, substantially as shown and described.

HENRY J. ROBINSON.
